UNITED STATES PATENT OFFICE

2,584,407

TANK BALL, STEM, AND GUIDE FOR WATER
CLOSET TANKS

Dale R. Wittke, Minneapolis, Minn.

Application August 27, 1948, Serial No. 46,493

5 Claims. (Cl. 4-56)

1

My present invention relates to water closet tanks, and more particularly, to a tank ball, stem and guide therefor.

It is well known that the present type of tank ball has a long upright stem that is loosely held in an upper guide and which tank ball, during the flushing of a water closet, is given a pendulum-like action as well as a circular movement about the projected axis of the seat for the tank ball as the same moves downwardly to its seat by the action of water draining from the tank. The erratic downward movement of the tank ball to its seat often causes the tank ball to improperly seat, with the result that water seeps from the filled tank, causing intermittent operation of the float to open the water intake valve and bring the water in the tank up to normal level.

The object of this invention is to provide a novel tank ball secured to the intermediate portion of a long stem held in upper and lower guides.

Other objects of this invention will be apparent from the following description, reference being had to the drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is a fragmentary view, partly in elevation and partly in section, showing the invention installed in a water closet tank; and

Fig. 2 is a view partly in plan and partly in section taken on the line 2-2 of Fig. 1.

The numeral 3 indicates a flush valve casing having a flaring upper end member 4, and an externally screw-threaded member 6, the upper annular edge portion of the former affording a seat 5 for a tank ball. This flush valve casing 3 extends through a hole 7 in the bottom member 8 of a water closet tank. Integral with the casing 3 is an external annular flange 9 above the tank bottom member 8. A washer 10 on the casing 3 is interposed between the tank bottom member 8 and the flange 9 to form a water-tight joint between said casing and bottom member 8. A nut 11 applied to the casing member 6 below the tank bottom member 8 impinges said bottom member and holds the washer 10 squeezed between the flange 9 and the tank bottom member 8.

2

An upright overflow pipe 12 at its lower end portion has screw-threaded engagement with a radially projecting fitting 13 integral with the flush valve casing 3 at the flange 9. A communicating passageway 14 in the fitting 13 leads from the overflow pipe 12 to the interior of the flush valve casing 3. An upper horizontal guide 15 is clamped onto the overflow pipe 12 and has on its outer end upper and lower members 16 having therein vertically axial bores 17 that are axially aligned with the tank ball seat 5.

The parts thus far described are common to the conventional water closet seat.

The rubber tank ball 18 shown is similar to the one now commonly used with the exception of the nut-acting member 19 embedded therein, which permits the use of a one-piece stem or a two-part stem 20, as shown. This stem 20 comprises an upper section 21 and a lower section 22, the former being identical with the stem now commonly used and at its lower end portion has screw-threaded engagement with the nut-acting member 19. In the upper end portion of the upper stem section 21 is an eye 23 for the customary connections for lifting the tank ball 18 from its seat 5 to flush the water closet. This upper stem member 21 extends loosely through the bores 17 and is guided thereby. The lower section 22 of the stem 20, at its upper end portion, extends into the tank ball 18 through the axial hole 24 in the bottom of the tank ball 18 and has screw-threaded engagement with the nut-acting member 19.

The lower stem section 22 extends loosely through an axial hole 25 in a bushing 26 that affords a lower guide for said stem member. The bushing 26 is mounted in a seat 27 on the outer end of a substantially radial arm 28. This arm 28 is integral with a flat spring 29 that is a little less than a complete circle. The normal diameter of the spring 29 is somewhat larger than the internal diameter of the valve casing member 6 in which it is mounted. To place the spring 29 in the valve casing member 6, the same is contracted to a smaller diameter than that of the internal diameter of the valve casing member 6, placed in said member and then released to expand into frictional engagement with the casing member 6, and being thereby held where positioned with the bushing 26 axially aligned with the bore 17 in the guide member 16 and the tank ball 18. On the upper end of the bushing 26 is an annular flange 30 that rests on the upper end of the seat 26 and thus prevents the bushing 26 from dropping through

said seat. Secured to the lower stem section is a weight 31 within the tank ball 18.

The purpose of making the stem 20 in two sections is to permit the use of the stem of an old installation, which corresponds to the upper stem section 21 shown in the drawing. In a new installation, the stem 20 may be all in one piece, in which case, screw-threads will be pressed from the intermediate portion thereof to a diameter larger than the diameter of the stem in order to permit the lower end portion thereof to be passed through the nut-acting member 19.

From what has been said, it will be understood that the invention described is capable of modifications as to details of construction and arrangement within the scope of the invention herein disclosed and claimed.

What I claim is:

1. A tank ball having a depending stem, a bushing affording a guide for the stem, and a circular spring insertable into a flush valve casing for yielding supporting contact with the internal wall of said casing, said spring having an inwardly projecting end portion provided at its inner end with a seat for the bushing.

2. A tank ball having a depending stem, a bushing affording a guide for the stem, and a flat circular spring insertable into a flush valve casing for yielding supporting contact with the internal wall of said casing, said spring having an inwardly projecting end portion that affords substantially a radial arm, the inner end portion of which is rolled upon itself to afford a seat in which the bushing is mounted, said bushing having an annular flange resting on the seat.

3. The combination with a flush valve casing, of a tank ball, a nut-acting member in the top portion of the tank ball at the axis thereof, said tank ball having in its bottom portion a large aperture axially aligned with the nut-acting member, a depending stem extending through said aperture and having at its upper end por-

tion threaded engagement with the nut-acting member, and a weight on the stem within the tank ball and removable with the stem from the tank ball through the aperture in said tank ball.

5. A tank ball having a depending stem, and a yieldingly compressible mount insertable into a flush valve casing and having yielding expansible contact with the internal wall thereof, said mount being free and independent of the tank ball for axial adjustment in said casing, said mount having at its axis a guide through which the stem extends for relative endwise movement with the tank ball.

15 6. A tank ball having a depending stem, and a yieldingly compressible mount insertable into a flush valve casing and having yielding expansible contact with the internal wall thereof, said mount being free and independent of the tank ball for axial adjustment in said casing, said mount having at its axis a sleeve-like seat, and a guide in the form of a bushing through which the stem extends for relative endwise movement with the tank ball, said guide having an annular flange resting on the upper end of the seat.
